Inventor

GEORGE W. WASHBURN,
By his Attorney

A. L. Ewin.

UNITED STATES PATENT OFFICE.

GEORGE W. WASHBURN, OF WEST NEW BRIGHTON, NEW YORK.

FASTENING FOR BUTTONS.

SPECIFICATION forming part of Letters Patent No. 320,517, dated June 23, 1885.

Application filed April 25, 1885. (No model.)

To all whom it may concern:

Be it known that I, GEORGE W. WASHBURN, a citizen of the United States, residing at West New Brighton, in the State of New York, 5 have invented a new and useful Improvement in Fastenings for Buttons, &c., of which the following is a specification.

This invention relates, primarily, to fastenings for cuff-buttons, collar-buttons, and shirt-studs, but may be embodied in part in scarf-pins and the like. It consists, first, in a novel construction of the "shoe" of the button or stud, whereby its insertion is facilitated, and at the same time a double hold on the respective sides of the button-hole is afforded; secondly, in the combination, with a rigidly-attached support for the back of the fabric formed by said shoe or the pin or pins of a scarf-jewel or the like, of a spring-detent having a serrated end, which bites the fabric in contact therewith until forced back by a card or the like, for the purpose of resisting the escape or withdrawal of buttons, &c., until they are purposely released by the wearer; 25 and, thirdly, in attaching said spring-detent by a hinge or pintle joint, whereby it is adapted to be made fast by hard-soldering, without the impairment of its elasticity by annealing.

A sheet of drawings accompanies this specification as part thereof.

Figures 1 and 2 of these drawings are edge views of a cuff-button illustrating this invention. Fig. 3 represents a section on the line 3 3, Fig. 2; Fig. 4, a front view of the shoe and post of the button as they appear before being united with the other parts; and Figs. 5 and 6 are additional edge views of the button, illustrating, respectively, the fastening and unfastening operations. Figs. 7 to 12, inclusive, illustrate other applications of the same fastening and modifications thereof, Fig. 7 being an edge view, and Fig. 8 a sectional back view, of a shirt-stud; Fig. 9, an edge view, and Fig. 10 a back view, of a jewel 40 too small to be conveniently provided with a hinged pin-tongue; and Figs. 11 and 12, respectively, an edge view and a back view of a scarf-pin provided with a hinge-attached spring-detent according to this invention.

Like letters of reference indicate corresponding parts in the several figures.

Said cuff-button, Figs. 1 to 6, inclusive, is provided with a shoe, *s*, in the form of a tapering oval with rounded edges, as shown in Fig. 4. This is rigidly united with the button proper or body *B* of the cuff-button by a nearly flat shank or post, *p*, having the form of a flat oval in cross-section, as shown in Fig. 3, and located near the larger end of the shoe, as shown in Fig. 4, and preferably away from the center of the button, as seen in Fig. 3, so that the long end of the shoe shall not project unnecessarily beyond the edge of the button. This construction of shoe and shank facilitates inserting the button in stiff cuffs without marring the linen, the shoe passing through the button-holes small end foremost, its long end coming to rest flat against the cuff inside and its short end or heel catching and holding within the cuff on the opposite side of the button-hole from that behind which said longer end holds, a secure double hold being thus afforded, as illustrated in Fig. 5, the flat shank of post *p* occupying the button-hole and precluding displacement by turning. As its central portion performs no function, the shoe may be made of wire, in skeleton form, as indicated in dotted lines in Fig. 4.

A spring-detent, *d*, having its free end serrated, as shown in Figs. 2, and 3, and its flat back resting against that of the button proper, engages by its teeth with the outer surface of the cuff, so as to resist the escape or withdrawal of the button, and thus renders the inserted button securely fastened or locked in automatically, as also illustrated by said Fig. 5. To unfasten it a card or the like is inserted between the spring-detent and the cuff, so as to disengage the teeth of the former from the latter, as illustrated in Fig. 6, and then, or at the same time, the cuff is unbuttoned from said heel end of the shoe, as indicated at the upper end of said Fig. 6, after which the button may be quickly removed, as indicated by the arrow in the figure.

To provide for securely uniting the parts with the aid of hard solder without annealing said spring-detent, a small hinge-tube, *h'*, is hard-soldered to said post *p* before the latter is attached to the button, as represented in Fig. 4, a pair of hinge-tubes being formed on the inner end of the detent, as shown in

Fig. 3, and a hinge-joint, h , is completed by inserting its pintle after the other parts are united.

The shoe-post and detent constituting the improved fastening may be made of one or more sizes, in quantity, and furnished to manufacturing jewelers, to be attached to buttons of different styles, as called for. A collar-button would have a fastening substantially 10 the same in all respects as said cuff-button.

The fastening of said shirt-stud, Figs. 7 and 8, operates on precisely the same principle as that of said cuff-button, and in construction it differs from the latter only in two 15 particulars—viz., its shoe s^x and post p^x are of round wire or jewelers' tubing, adapting them to eyelet-holes, and its spring-detent d^x is attached to the back of the button proper or body B^x by soft solder behind the post, 20 having for this purpose a bifurcated end, e , to embrace the latter, illustrating this and analogous ways of rigidly attaching the spring-detent in either application thereof.

The fastening of said small jewel, Figs. 9 and 25 10, consists in part of a short rigid double pin, p^y , forming a support for the back of the fabric, substantially similar to the long end of said shoe s , to coact with a spring-detent, d^y , with which the jewel setting or body B^y is provided. The spring-detent is attached in this 30 modification to the back of said body B^y by a hinge-joint, h^y , the fixed part of which may be hard-soldered on without subjecting the spring-detent to annealing heat, as in the form 35 first described.

The fastening of said scarf-pin, Figs. 11 and 12, is composed of a spring-detent, d^z , similar 40 to the one just described, in combination with a short rigid pin, p^z , the latter performing the functions of said shoe s as a support for the face of the fabric to coact with said spring-detent. Said spring-detent in each application

thereof operates automatically to fasten the article to which it is attached against escape or withdrawal, and is unlocked by inserting 45 a card or the like between its serrated end and the fabric, with which the latter interlocks. Other analogous applications and modifications of the same will occur to those skilled in the art. 50

Having thus described my said improvement in fastenings for buttons, &c., I claim as my invention and desire to patent under this specification—

1. The combination, with the body of a 55 button or the like, of a rigidly-attached flat post perpendicular to its back, and a shoe in the form of a long tapering oval rigidly united with said post near its larger end, the post being transverse with reference to the shoe, and 60 said larger end of the shoe projecting as a rigid heel, substantially as herein specified.

2. The combination, with the body of a 65 button or the like, of a rigidly-attached support for the back of the fabric, to which it is thereby connected, adapted to be inserted endwise through the fabric, and a spring-detent having a serrated end opposed to said support to resist escape or withdrawal, substantially as herein specified. 70

3. The combination, with the body of a 75 button or the like, of a rigidly-attached support for the back of the fabric, to which it is thereby connected, adapted to be inserted endwise through the fabric, and a spring-detent having a serrated end opposed to said support, and attached by a hinge-joint, substantially as herein specified, for the purpose set forth.

GEO. W. WASHBURN.
